MAX E. GYSEL, OF WILKINSBURG, PENNSYLVANIA, ASSIGNEE TO WESTINGHOUSE ELECTRIC & MANUFACTURING COMPANY, A CORPORATION OF PENNSYLVANIA.

CONTROLLING DEVICE FOR BRUSH-HOLDER MECHANISMS.

1,389,137.

Specification of Letters Patent. Patented Aug. 30, 1921.

Application filed November 7, 1917. Serial No. 200,668.

To all whom it may concern:

Be it known that I, MAX E. GYSEL, a citizen of the Republic of Switzerland, and a resident of Wilkinsburg, in the county 5 of Allegheny and State of Pennsylvania, have invented a new and useful Improvement in Controlling Devices for Brush-Holder Mechanisms, of which the following is a specification.

10 My invention relates to brush-holder mechanisms for dynamo-electric machines and it has particular relation to brush-holder mechanisms employed in connection with single-phase motors of the commuta- 15 tor type that are adapted for repulsion operation during the starting period and for induction operation after a predetermined speed has been attained.

20 The object of my invention is to provide a simple and effective device for controlling the operation of the brush-holder mechanisms of machines of the above-designated type.

25 Repulsion-induction motors usually comprise means for maintaining the brushes in engagement with the commutator cylinders while the machines are operating as repulsion motors during the starting period and further means for either lifting or releas- 30 ing the pressure upon the brushes after a predetermined speed is attained and it is desirable for the machines to operate as induction motors. Such means usually comprise centrifugally-actuated devices that are 35 mounted on the shafts of the motors and are adapted to actuate reciprocating sleeves for controlling the brush-holder mechanisms. Difficulties have heretofore been encountered because the wear between the relatively ro- 40 tatable parts of the above-described devices impairs their effectiveness and efficiency by allowing the brushes to engage, or be disengaged from, the commutator cylinders at the wrong time.

45 According to my invention, I provide a device for controlling the operation of the brushes in which the relatively rotatable parts are in engagement during only very brief period and the operation of which is 50 entirely independent of any sluggishness of the centrifugally-actuated members.

In the accompanying drawings, Figure 1 is a sectional view of a portion of a motor provided with a brush-holder mechanism 55 constructed in accordance with my inven-

tion; and Fig. 2 is a sectional view along the line II—II of Fig. 1.

The motor comprises a shaft 1 that is rotatably mounted in bearings 2, only one of which is shown. A core member 3 is 60 mounted on the shaft 1 and is provided with a winding 4 that is suitably connected to the conducting segments of a commutator cylinder 5. The commutator cylinder 5 is of the radial type and is carried by a hollow 65 cylindrical member 6 that is mounted on the shaft 1 adjacent to one end of the core member 3.

A brush-holder-supporting ring 7 is mounted on the bearing bracket 2 in concentric relation with the shaft 1. The supporting ring 7 is provided with a plurality of radial arms 8 and seats 9 adjacent thereto upon which are mounted members 10 in spaced parallel relation to the arms 8. 75 Brushes 11 are mounted between the arms 8 and the members 10 and are adapted to be maintained in engagement with the face of the commutator cylinder 5 by brush-biasing plates 12 that are maintained in 80 sliding relation to the arms 8 by pins 13 coacting with slots 14 that are provided in the plates. The plates 12 are further provided with oppositely disposed projections 15 and 16. A finger 17 is pivotally mounted 85 on each arm 8 and is adapted to be biased in the direction of the commutator cylinder 5 by a U-shaped spring 18 that is connected, at its ends, to the finger 17 and to the arm 8, respectively. The spring 18 is connected 90 to the arm 8 by means of a pin 19 that is located in a slot 20 which is provided in the plate 12. The finger 17 is adapted to engage the projection 16 and so cause the pro-

jection 15 to maintain the brush 11 in engagement with the face of the commutator cylinder 5, as shown in full lines in Fig. 1. The finger 17 is also adapted to be biased in another position of the spring 18, as shown in dotted lines in Fig. 1, in which 100 position it is entirely disengaged from the brush-biasing plate 12. The movement range of the finger 17, in the latter position, is limited by a reduced portion 21 that engages the end of a slot 22 which is provided in the wall of the brush-supporting ring 7. The portion 21 projects through the slot and beyond the inner surface of the ring 7 for a purpose which will hereinafter be described.

A hollow cylindrical sleeve 23 is spaced from, and slidably mounted upon, a shaft 1 by an annular end flange 24 which engages the surface of the shaft 1, and by a collar 5 25 that is adjustably mounted on the shaft 1. The sleeve 23 is provided with similar annular projections 26 and 27 that are spaced apart and are located at the respective sides of the projecting portion 21 of the finger 10 17. The sleeve 23 is further provided with an annular groove 28 within which is located a helical spring 29 of ring form. A flexible electric conductor 30 is threaded through the spring 29 and is adapted to 15 short circuit the several turns thereof. Governor weights 31 are pivotally mounted on the shaft by pins 32 and are provided with projections 33 which are adapted to engage the flange 24 of the sleeve 23 and move it in a 20 left-hand direction when the weights 31 move outwardly in a counter-clockwise direction under the influence of centrifugal force. A compression spring 34 is located within the sleeve 23, between the flange 24 25 and the collar 25, and is adapted to bias the sleeve in a right-hand direction and to retain the weights 31 in a retracted position with respect to the shaft 1. In the above 30 description, the arrangement and form of the spring 29 forms no part of the present invention but is substantially as shown and described in Patent No. 1,090,328.

Having described the various parts entering into my invention, the operation is as 35 follows. When the shaft 1 is at rest, the positions of the various parts are as shown in the full lines in Fig. 1, in which case, the brushes 11 are maintained in engagement with the commutator cylinder by the fingers 40 17. The sleeve 23 is then in the extreme right hand position, the short-circuiting spring 29 is disengaged from the inner cylindrical surface of the commutator cylinder 5, and the motor is adapted to start as a 45 repulsion motor. As the motor accelerates, the governor arms 31 tend to move outwardly about their pivots, under the influence of centrifugal force, and to move the sleeve 23 in the left-hand direction against 50 the action of the spring 34. As the sleeve 23 moves in the direction indicated by the arrow, the projection 26 engages the projecting portion 21 of the finger 17 and moves it about its pivotal axis. When the finger 17 55 is moved beyond its neutral position, the spring 18 acts in the other direction and quickly throws the finger 21 against the end of the slot 22. At the same time, the short-circuiting spring 29 engages the inner cylindrical surface of the commutator cylinder 5 and, as the brushes 11 are then free to be 60 disengaged from the commutator cylinder by the end thrust of the shaft, the machine operates as an induction motor. If the motor 65 is stopped or the speed of the shaft 1

falls below a predetermined value, the governor arms move inwardly, and the sleeve 23 is moved in the right-hand direction by the spring 34. The projection 27 of the sleeve 23 then engages the projecting portion 21 70 of the finger 17, after a slight degree of movement, and carries it through the neutral position, whereupon the finger 17 quickly engages the projection 16 of the brush plate 12 and returns the brushes into 75 engagement with the commutator cylinder. The motor is then again adapted to operate as a repulsion motor.

From the foregoing and from an inspection of Fig. 1 of the drawings, it is apparent that the projections 26 and 27 of the sleeve 23 are in engagement with the finger 17 during only very brief periods. It will be seen that, in order for the projection 26 to carry the finger 17 through its neutral position, it will be necessary for the sleeve 23 to move through such a distance that the projection 27 will be moved beyond the extreme left-hand position of the finger 17, as shown in dotted lines in Fig. 1. Furthermore, the brushes 17 will be returned to the commutator cylinder with a positive action whenever the speed falls below a predetermined value so that the operation of the motor will not be affected by sluggish operation of the governor arms during small changes in the speed of the motor, and the effectiveness of the short-circuiting device will not be impaired by wear between the relatively movable parts of the controlling 95 device.

While I have shown my invention in its simplest and preferred form, it is not so limited but is susceptible of various minor changes and modifications within the spirit 100 and scope of the appended claims.

I claim as my invention:

1. In a dynamo-electric machine, the combination with a commutator cylinder, a brush holder and a brush slidably mounted thereon, of a member adapted to exert yieldable pressure in opposite directions from a neutral position to engage, or to be disengaged from, said brush, and automatic means for moving said member through 115 the neutral position.

2. In a dynamo-electric machine, the combination with a commutator cylinder mounted on a rotatable shaft, a brush holder and a brush slidably mounted thereon, of a member adapted to exert yieldable pressure in opposite directions from a neutral position to engage, or to be disengaged from, said brush, and means responsive to the speed of the rotatable shaft for moving said member through the neutral position.

3. In a dynamo-electric machine, the combination with a commutator cylinder mounted on a rotatable shaft, a brush holder and a brush slidably mounted thereon, of a mem- 130

- ber adapted to exert yieldable pressure in opposite directions from a neutral position to engage, or to be disengaged from, said brush, and a device slidably mounted on 5 the shaft and responsive to changes of speed thereof for moving said member through the neutral position.
4. In a dynamo-electric machine, the combination with a commutator cylinder mounted on a rotatable shaft, a brush holder and a brush slidably mounted thereon, of a member adapted to exert yieldable pressure in opposite directions from a neutral position to engage, or to be disengaged from, said brush, and a centrifugally-actuated device 10 carried by the shaft for moving said member through the neutral position.
5. In a brush-holding device, the combination with a brush-box and a brush slidably mounted therein, of a member mounted on said brush-box and adapted to exert yieldable pressure in opposite directions from a neutral position to engage, or to be disengaged from, said brush.
- 20 6. In a brush-holding device, the combination with a brush-box and a brush slidably mounted therein, of a member pivotally mounted on said brush box and a member
- slidably mounted on said brush box and provided with projections, one of which 30 is adapted to engage the brush, the said pivotally mounted member being adapted to exert yieldable pressure in opposite directions from a neutral position to engage the other of said projections or to be entirely disengaged from said 35 slidably mounted member.
7. In a dynamo-electric machine, the combination with a commutator cylinder mounted on a rotatable shaft, a brush holder 40 and a brush slidably mounted thereon, of a pressure-exerting member adapted to exert yieldable pressure in opposite directions from a neutral position to engage, or to be disengaged from, said brush, and a sleeve 45 slidably mounted on said shaft, a governor adapted to move said sleeve longitudinally on said shaft in response to changes of speed, said sleeve being provided with projections whereby said pressure-exerting member is 50 moved through the neutral position.

In testimony whereof, I have hereunto subscribed my name this 31st day of Oct. 1917.

MAX. E. GYSEL.
